UNITED STATES PATENT OFFICE.

JAMES HUMES, OF NEW YORK, N. Y.

METHOD OF AND APPARATUS FOR MAKING ICE.

SPECIFICATION forming part of Letters Patent No. 625,447, dated May 23, 1899.

Application filed February 2, 1899. Serial No. 704,255. (No model.)

To all whom it may concern.

Be it known that I, JAMES HUMES, a citizen of the United States, residing at New York city, borough of Manhattan, county and State of New York, have invented certain new and useful Improvements in Methods of and Apparatus for Making Ice, of which the following is such a full, clear, and exact description as will enable any one skilled in the art to 5 which it appertains to make and use the same, reference being had to the accompanying drawings, forming part of this specification.

In the manufacture of ice blocks by means of metallic cans to the whole or parts of the 15 sides or bottom of which the freezing medium is applied the ice forms upon the walls of the interior of the can and gradually meets near the center thereof, thus forming a single block of ice. It has been customary in thus manufacturing ice to employ a can either entirely 20 free from jacketing or insulation for retarding the freezing or partially or wholly covered on certain sides with such insulation and to subject the uninsulated or unprotected 25 portions of the can to the freezing medium. The block of ice formed by the use of such apparatus invariably contains a comparatively 30 large core or body of white ice, with the sediment therein, which core is so spread out or diffused laterally that it materially lessens 35 the commercial value of the ice. By experiments I have found that by dispensing entirely with insulation or means for retarding the freezing at the sides of the ice-mold and 40 confining such retarding means exclusively to the bottom of the ice-mold, so that the freezing medium can be directly applied only to the sides, the objectionable core is practically 45 prevented from forming in the ice block, and in instances where it does form it is minimized or restricted to a comparatively small area or vertical stratum, which being centrally located on the line on which the original block is subsequently cut to divide it into 50 commercial blocks or cakes is removed in such cutting, and therefore practically does not show itself in the same.

I have illustrated types of my invention in the accompanying drawings, wherein—
50 Figure 1 is a vertical section of a freezing-mixture tank or compartment with one of my improved ice-molds set therein and also

shown in vertical section. Figs. 2 to 5, inclusive, show end views of different forms of my improved ice-mold, the lower portions of 55 which are broken away and the bottoms thereof, together with the insulation, are shown in vertical section. Fig. 6 is a perspective view of the form of ice-mold shown in Fig. 3, the lower portion of one end of the mold 60 being broken away and the bottom and insulation being in vertical section. Fig. 7 is a perspective view of another form of my improved ice-mold with the lower portion of one end thereof broken away and shown in 65 vertical transverse section. Fig. 8 is a top view of a finished block of ice taken from the ice-mold and having the cutting-lines indicated by dotted lines.

Referring to the drawings, in which like 70 numbers of reference indicate like parts throughout, 2 is an open-top metallic ice-mold rectangular both in its cross and horizontal section and having a slight taper from the top to the bottom, where it is smaller than at 75 the top. The base of the mold 2 is preferably formed with a downwardly-projecting flange 3 for elevating the bottom 4 a convenient distance to receive the jacketing or insulating material 5, which in the construction shown 80 I preferably make fast to the bottom of the mold, so that it constitutes a permanent part thereof. However, this insulating material 5 may be detachable or so arranged that it may be applied and kept in its place temporarily and during the freezing process. This 85 insulating material 5 is preferably made from a thick piece of wood, and I show several ways of applying it.

In Fig. 1 the insulating material 5 for retarding the freezing consists in a thick piece 90 of suitable material covering the entire bottom of the ice-mold on its under side, and it is made to fit snugly within the four flanges 3, formed around the bottom thereof.

In Fig. 2 the insulating-piece 5 covers the 95 entire bottom of the mold, as in Fig. 1, but is not so thick as in the latter construction in order that an air-space 6 may be provided between the bottom of the mold and the layer 100 of material 5. At a suitable point in the insulation 5 there is formed a hole 7, in which fits a stopper or plug 8 for closing it. By this means when the ice-mold is removed with its

block of ice warm water or air may be injected into the space 6 to thaw the ice from the bottom.

In the construction shown in Figs. 3 and 6 5 the piece of insulating material 5 extends entirely across the bottom of the mold, as in the constructions described, and has its inner face formed with longitudinal recesses or chambers 9, from which extend perforations 10, leading to the exterior of the insulation. In using this form warm water or air may be injected through the holes 10 into the chambers 9, so as to come in contact directly with the metallic bottom of the mold in order to 15 thaw the block of ice at such point.

In Fig. 4 the insulating material 5 extends from end to end across the under side of the bottom of the mold, as in the constructions described, but does not extend the full width 20 of the bottom, so that a space 11 is provided at each side of the insulation, and into these spaces warm water or air may be introduced to thaw the block of ice at the bottom when taking it out of the mold.

In Fig. 5 I show the insulation 5 as divided 25 up into five strips, which run the full length of the ice-mold and are spaced from each other, so as to provide the recesses 12, into which warm water or air may be introduced 30 when thawing out the ice block.

In the construction shown in Fig. 7 the strip of insulating material 5 extends around the under side of the bottom of the mold, in the angle formed between such bottom and 35 the flange 3, and as an extra precaution for excluding the freezing medium from beneath the ice-mold I apply to the insulating-strips 5 a soft flap 16, made, for example, of rubber, which extends all the way around the ice- 40 mold and serves as a seal between the base of the ice-mold and the bottom or floor of the compartment in which it is set.

In Fig. 1 the ice-mold is shown as placed 45 in a tank 13, containing the freezing medium or brine 14, the level of which is some little distance below the top of the mold. It will be noted that in this arrangement the freezing medium is applied directly to practically the entire sides of the mold, but is not applied 50 at all to the bottom thereof. By thus excluding the direct action of the freezing medium from the bottom of the molds the freezing process is retarded at such point only. This retardation at the bottom while the ice is forming more rapidly on the sides of the mold brings about an effect which I have illustrated 55 in Fig. 1 by dotted lines.

In the freezing process the ice forms simultaneously upon the interior of the walls of the 60 ice-mold and thickens inwardly toward the center of the mold in a horizontal direction. As the bottom of the ice-mold is protected or insulated, the formation of ice is so retarded at that point that the ice is practically prevented from forming or building upwardly from the bottom. This permits the ice to 65 form horizontally inwardly along the bottom

from the direction of the sides in the same manner as at other points above the bottom. The conductivity of the metallic bottom of 70 the ice-mold somewhat quickens the formation of the ice horizontally near the bottom and causes the bodies of ice on the walls to thicken near the lower part a little faster than near the upper part, which results in the inner faces of the bodies of ice being inclined, so that considering two oppositely-located portions of the forming ice there is a wedge-shaped space or cavity between such parts, with the narrowest part of the cavity lying 75 toward the bottom of the ice-mold. As the formation of ice increases, the opposite bodies of ice meet first at the bottom of the ice-mold, and the cavity is gradually closed from the bottom upwardly by the horizontal thickening of the forming bodies of ice. This wedge-shaped cavity at one stage of the formation of the ice block is indicated by the dotted lines *a a* in Fig. 1, which show an end view of the wedge-shaped cavity. As the ice forms 80 simultaneously on all sides of the ice-mold, all the dimensions of the central cavity gradually decrease, and this serves to force or squeeze the suspended air and sediment toward the central plane, so that eventually the 85 remaining air and sediment are frozen in a comparatively and uniformly thin central layer or stratum having a trend that is vertical and longitudinal the ice-mold, but falling a considerable distance short of the ends of the 90 block. This core stratum is indicated in its final position in end view by the dotted line *b* in Fig. 1 and in plan view by dotted line *c d*, Fig. 8, and it is so concentrated and centralized as to be practically eliminated in cutting 95 up the original block into marketable cakes, as hereinafter described. This closing up of the cavity in the peculiar manner described can be illustrated by two blocks with their lower edges placed together and their opposing 100 faces inclined to the vertical, so as to leave a V-shaped space between them, and then gradually moving the two together to close the V-shaped cavity. In this illustration the bottom of the V-shaped space represents practically 105 the bottom of the ice-mold, and the contraction of the V-cavity by the movement of the two blocks toward each other represents the horizontal thickening of the opposing bodies of ice. An important effect of this local retardation of the freezing process at the bottom of the ice-mold is that the air which is suspended in the water at its lowest depths is given a longer time to pass upwardly through the water and move in toward the center of the 115 body of water and also a more desirable formation of grain, so that by the time the opposing bodies of ice meet the quantity of air has been materially reduced and all that remains has been centralized in a vertical stratum lying between the opposing bodies of ice formed on the sides. I preferably make the ice-mold of such width that the original block formed in the 120 ice-mold may be divided on this vertical cen-

tral stratum, so that the ice which is removed by such cutting is practically all of the white ice which occurs in the original block, and I am thereby enabled to commercially produce 5 a clear and practically coreless ice and with the grain characteristics of what is known as "plate" ice. In practice I make the ice-mold about twenty-two inches wide by forty-four long and forty-four inches deep, such dimensions giving to the ice-mold about four times the capacity of the ordinary ice-mold, which is generally eleven by twenty-two by forty-four. The size of the ordinary commercial cake of ice being about eleven by twenty-two by forty-four, I cut the large block formed in my ice-mold on the lines shown in Fig. 8, and thereby obtain four cakes of such dimensions. Upon removing the ice block from the mold it may be cut from one side to the other on line *e f* 15 and then on line *g h*, which will give two clear cakes of ice of commercial size eleven by twenty-two with practically no trace of the core, as each of the cutting-lines *e f* and *g h* fall about the point where the thin core 20 stratum *c d* terminates. The remaining piece may then be cut on the line *c d*, thereby obtaining two more blocks of the same commercial size, and in making this cut the core stratum will be practically removed, thereby 25 leaving a clear cake of ice. Obviously the same practically coreless cakes of ice may be cut from this block by making the first cut longitudinally through the entire block on the same plane as the line *c d* and then dividing the two halves into equal parts on a plane at right angles to *c d*. In other words, 30 by cutting on two planes normal to each other four practically coreless cakes may be obtained. It will be noted that each of the four 35 commercial cakes which I obtain after cutting the original block is practically what is known as "plate" ice, having the same characteristic grain and being free from core. Of course the dimensions of the ice-mold may be varied 40 as desired, but the same result will be obtained as that described in Fig. 1.

It will be observed that where it becomes necessary to draw the ice block from the mold before the central cavity has been closed 45 up this can be done by the use of the particular ice-mold which I have described, for in such case the original block when cut up into commercial-sized cakes is cut on the plane of the cavity, so that none of the cakes 50 will show a defective cavity, as would be the case if the ice were drawn from the ordinary eleven by twenty-two can before the cavity was closed.

With the several different constructions 55 shown the freezing process takes place in substantially the same way as described in reference to Fig. 1, and I obtain the same good results in each case. In the forms shown in Figs. 3 to 7, inclusive, any freezing mixture or brine that may enter the recesses formed in the insulation as the mold is set in the tank will remain practically confined therein

and soon reach such a high temperature that it will not materially interfere with the retardation of the freezing process which I seek 70 to effect at that point. In none of these forms will the freezing-brine circulate through the recesses, as such places are practically closed by the floor of the tank when the mold is in its proper position. The recesses through 75 which access is gained to the under side of the bottom 4 of the ice-mold may extend only part way the length of the same instead of practically the entire length thereof, as shown. 80

I wish to be understood as not limiting myself to the particular constructions herein set forth, as various modifications may be made in the same without departing from the spirit of my invention. The insulation or protecting means for the bottom of the ice-mold instead of being attached thereto as I have herein set forth may be itself located on the bottom or floor of the tank or compartment in which the ice-mold is placed when the 90 freezing takes place.

Having thus described my invention, what I claim, and desire to secure by Letters Patent, is—

1. An ice-mold having its bottom practically wholly insulated or protected to retard the freezing process at the bottom and having the entire sides thereof free from insulation whereby the freezing medium may be directly applied to all parts of the mold other 100 than the bottom thereof whereby there is produced a single block of ice having a thin core located or having a trend between a plurality of substantially equal rectangular portions thereof, substantially as and for the 105 purpose set forth.

2. An ice-mold having its bottom provided with insulating or protecting means for retarding the freezing process at the bottom whereby there is produced a single block of 110 ice having a thin core located or having a trend between a plurality of substantially equal rectangular portions thereof, said insulating or protecting means being provided with one or more chambers or recesses for 115 placing the exterior of the bottom of said ice-mold in communication with the under side of the insulating or protecting means, substantially as and for the purpose set forth.

3. An ice-mold having its bottom provided 120 with insulating or protecting material whereby there is produced a single block of ice having a thin core located or having a trend between a plurality of substantially equal rectangular portions thereof, said material being formed with one or more grooves or recesses upon the inner side thereof and ducts leading from said grooves or recesses through said insulating or protecting material, substantially as and for the purpose set forth. 125

4. The combination of a portable ice-mold having its bottom provided with insulating or protecting means for retarding the freezing process at the bottom when placed in the

freezing medium whereby there is produced a single block of ice having a thin core located or having a trend between a plurality of substantially equal rectangular portions thereof, and a seal of soft material placed around the bottom of said mold, substantially as and for the purpose set forth.

5. The herein-described method of producing practically coreless cakes of ice of commercial size, which consists in forming a block of ice two or more times the horizontal sectional area of the commercial size of cake by freezing the body of water from the direction of all sides but retarding the freezing from the bottom upwardly, thereby centralizing the ice core and concentrating it in a thin vertical stratum extending centrally of the ice block, and then cutting the block into cakes of commercial size, one of said cuts being on the core stratum to eliminate the core, substantially as described.

6. The herein-described method of producing practically coreless cakes of ice of commercial size, which consists in forming a block of ice two or more times the horizontal sectional area of the commercial size of cake by

freezing the body of water so as to centralize the ice core and concentrate it in a thin vertical stratum extending centrally of the ice block, and then cutting the block into cakes 30 of commercial size, one of said cuts being on the core stratum to eliminate the core, substantially as described.

7. The herein-described artificially-formed block of ice adapted to be divided into cakes 35 of practically commercial size, the same consisting of a plurality of substantially equal rectangular and practically coreless portions separated at least along one line of division by a uniformly thin vertical core stratum extending centrally of the ice block and which core stratum is practically eliminated by cutting into commercial cakes, substantially as set forth.

In testimony whereof I have hereunto set 45 my hand, this 1st day of February, 1899, in presence of the two subscribing witnesses.

JAMES HUMES.
